SPRING ASSEMBLY

David I. Levine, Swampscott, Mass., assignor to
 Spring Unit Development Co., Lynn, Mass., a
 partnership

Application January 11, 1945, Serial No. 572,359

8 Claims. (Cl. 5—270)

1

This invention relates to spring assemblies made up of a multiplicity of coil springs and designed for use in bed springs, cushions, mattresses and chair and seat backs, in conveyances or elsewhere. The invention deals particularly with spring assemblies wherein tie wire elements are used for assembling the springs into a unitary structure.

A main object of the invention is to provide a tie wire-coil assembly which is economical and easy to assemble, yet has improved durability and integrity by reason of a more effective and improved mode of interlock.

With regard to economy, the interlock of this invention utilizes a tie wire of relatively simple conformation and of a type heretofore used, but assembles such tie wire with the convolutions of juxtaposed springs in a novel manner predicated upon the utilization in cooperation with the tie wire of a specially designed clip. Inclusion of the clip has a number of important advantages from the standpoint both of improved structural interlock and of ease of assembly. These advantages will be more readily understood when considered in connection with the description of the interlock, examples of which are shown in the accompanying drawings in which,

Fig. 1 is a plan of a corner portion of a spring assembly including interlocks embodying the invention;

Fig. 2 is a perspective view of the clip of the invention;

Figs. 3, 4 and 5 are perspective details illustrating successive steps in the operation of assembling the interlock of the invention;

Fig. 6 is a cross-sectional detail of the interlock in the stage of assembling operation shown in Fig. 5;

Fig. 7 is a cross-sectional detail taken along the lines 7—7 of Fig. 1;

Fig. 8 is a side elevation of the interlock; and

Figs. 9 and 10 are detailed views, corresponding to the views of Fig. 5 and Fig. 7, of a modified form of interlock.

The invention is adapted for particular use in connection with coil springs, for example of the double or single cone type, as described in my prior Patents Nos. 2,197,131 and 2,116,796.

As described in these patents, such coil springs are assembled in spaced rows of juxtaposed coils and are held in these relationships by the interposition of tie wires. Such an assembly is shown in the accompanying drawings wherein the coil springs are identified by the reference

2

numerals 10 and the tie wires by the reference numeral 12.

The tie wire utilized in the assembly interlock of this invention is of the same simple conformation as that shown in my prior Patent No. 2,116,796 and comprises a wire having two or more spaced offset loops 14, one of which offset portions is shown in Fig. 4. The operation of forming the tie wire utilized in the present interlock is therefore simpler than that shown in my prior Patent No. 2,197,131. Improved interlock is accomplished however by the use of a novel clip shown in its preferred form in Fig. 2.

This clip 15 may be formed from sheet stock, as of metal. The stock is apertured centrally and folded over longitudinally to form a U-shaped fold 20 spanning the space intermediate parallelly extending base members 30 and 31. In the preferred form shown, the bases 30 and 31 lie in a plane substantially normal to the planes of the legs 21 and 22 of the fold 20. The fold 20 is interrupted by a recess 24 formed by the aperture in the stock, to provide a transverse passageway through the legs 21 and 22 of the fold 20 for a purpose to be described. As will be understood, these clips 15 may be readily stamped out of sheet metal and die-pressed to the configuration shown.

To simplify the explanation of the invention, the manner of preferred assembly of the clip 15 is illustrated by the showing of Figs. 2, 3, 4 and 5 and a description of these steps will be given for the purpose of describing the structure of the interlock.

As a first step, the clip 15 is suspended over an arc of an end convolution 34 of one coil unit 10, with an arc of the end convolution extending through the longitudinal channel formed by the fold 20 of the clip 15 in the manner shown in Fig. 3.

The spring unit having the end convolution 34 with its clip 15 suspended thereon is then passed over an end convolution 36 of an adjacent unit 10 so that the end convolution 34 overlaps the end convolution 36 and the base member 31 of the clip 15 passes under end convolution 36, all as shown in Fig. 4.

At this stage of the operation the tie wire 12 with its offset portion 14, shown in Fig. 4, is brought into position to be passed transversely of the clip through the apertures formed in the legs 21 and 22 of fold 20 by the recess 24, and between the clip base members 30 and 31 and the portion 34a of spring convolution 34 seated in the channel of fold 20. The offset portion

14, the terminal portion 14a of which may be pre-bent to the form shown in Fig. 4, is then passed beneath the end convolution 36 so that the parts take the position shown in Figs. 5 and 6, with the longitudinal portions of the tie wire 12 lying on clip base 30 and underlying, on both sides of clip 15, end convolution 36 and with the terminal portion 14a of the offset 14 extending beyond the overlapped portion of end convolution 36.

When the parts have been brought to this position, the end portion 14a may be crimped to interlock the tie wire with the clip and end convolutions. In the form shown the end portion is crimped upwardly about the convolution 36 toward the apex of fold 20 into the position shown in Figs. 1, 7 and 8. During this crimping operation, the clip 15 is deformed, and the fold 20 may, depending upon the pressure used in the crimping operation, even be collapsed to bring its opposed legs 21 and 22 into engagement with each other, as shown in Fig. 7, to firmly lock the end convolution 34 in the fold. At the same time there may be some deformation of the base members 30 and 31 as shown in Figs. 7 and 8. The crimping operation also acts to firmly lock the end convolution 36 between the tie wire crimped portion 14a and the outer sides of legs 22 of clip 15.

By reason of the particular assembly, a firm engagement of the end convolutions 34 and 36 may be attained without excessive crimping pressure, and the parts are so arranged that the crimping operation may be readily performed manually with pliers or the like.

It has been found that an assembly as above described acts to hold securely the end convolution of the units 10, especially the end convolution 34. The fold 20 restrains rotation of end convolution 34 about the axis of its coil while the engagement of the tie wire offset 14 and outer sides of leg 22 of fold 20 with end convolution 36 restrains end convolution 36 from rotation about the axis of its coil. The assembly as a whole therefore provides a more durable interlock which is not so loosened by repeated depression and release of the spring units of the assembly during use as to permit distortion from the original coil positions. Nevertheless the interlock does not interfere with any required flexing of the end convolutions such as is necessary in permitting desirable depression and release of the coil units.

The improved interlock thus secures superior results with the expenditure of less force during the assembly operation.

A further advantage of the interlock is that the same tie wire may be used for different sizes of coil convolutions by merely substituting a larger or smaller clip 15.

When a wider clip is used for the same size of spring, the assembly may have the modified form of interlock shown in Figs. 9 and 10. In this instance, the assembly is made by passing the clip 40 over the two adjacent convolutions which are received in the channel of the clip 40. The tie wire offset portion 14 is then passed through the apertures in the legs of the fold of the clip 40 to the position shown in Fig. 9 and thereafter the end convolution 14a of the offset is crimped upwardly over both end convolutions to the position shown in Fig. 10. During this crimping operation the leg 42 of clip 40 may be bent towards the other leg of the clip 40 to the position shown in Fig. 10 to clamp the end convolutions tightly against each other, against the clip and against tie wire 76 which is crimped to the clip 40.

offset 14. As shown by this modified form of clip, the outwardly extending base 50 may be provided on only one side of the centrally apertured clip, namely, on the side which receives the tie wire 12. Bending in of leg 42 moves the bottom edge of the leg into a protected position where it will not be so likely to catch on other parts.

In Figs. 9 and 10, the channel of the clip 40 is sufficiently wide to accommodate arcs of end convolutions of both coils 34 and 36 in edge-to-edge relation in the same plane and without overlapping.

The improved interlocks herein described may be utilized between all the spring units of each row, thereby forming a group of springs all fastened with the improved interlock of this invention.

I claim:

1. A spring assembly comprising a plurality of 20 rows of coil spring units, tie wires for tying together convolutions of units in one row to units in another row; each tie wire having offset loops spaced longitudinally therealong, and U-shaped clips at junctures of the tie wires with the units 25 which they tie, the legs of each of said clips enfolding a portion of a convolution of a unit in one row, both legs of each clip being apertured, and an offset loop of a tie wire extending transversely from one side of each clip through said 30 apertures below said enfolded convolution portion and being crimped around a portion of a convolution of an adjacent unit in the same row to interlock at each of said junctures said two convolutions, said tie wire and said clip.

35. 2. A spring assembly as claimed in claim 1, wherein the offset loops of the tie wires are crimped around the adjacent convolution portions in a direction towards the apexes of the U-shaped clips.

40. 3. A spring assembly comprising a plurality of rows of coiled spring units, convolutions of adjacent units in said rows being in overlapping relation, tie wires for retaining units in one row on spaced centers with units in another row, each tie 45 wire having offset loops spaced longitudinally therealong, and U-shaped clips at junctures of said overlapping convolutions, one leg of each clip extending between the overlapped portions of the adjacent convolutions with a portion of one of said convolutions lying enfolded between the legs of each clip, both legs of each clip being apertured, and an offset loop of a tie wire extending transversely from one side of each clip through said 50 apertures below said enfolded convolution portion to lock said enfolded convolution portion in the clip and being crimped around a portion of the other convolution to lock said other convolution against the outside of the leg at the other side of the clip.

60. 4. A spring assembly as claimed in claim 3, wherein a convolution of an intervening spring unit in one of said rows lies outside of the leg of a clip at the juncture of the intervening spring unit with an adjacent unit in the same row on one side thereof, and is enfolded between the legs of a clip at the juncture of said intervening unit with the adjacent unit in said row on the other side thereof.

65. 5. A spring assembly as claimed in claim 3, 70 wherein the overlapped portions of the convolutions locked to a clip both lie on the same side of the tie wire loop extending through the legs of that clip.

6. A spring assembly as claimed in claim 3, 75 wherein a convolution enfolded in a clip over-

lies the convolution locked against the leg of that clip and both convolutions overlie the tie wire loop extending through the legs of the clip.

7. A spring assembly comprising a plurality of rows of coil spring units, tie wires for retaining units in one row on spaced centers with units in another row, each tie wire having offset loops spaced longitudinally therealong, and flanged U-shaped clips at junctures of adjacent coils in each row, the legs of each clip enfolding a portion of a convolution of a unit in one row, both legs of each clip being apertured, and a tie wire being seated on the flange of each clip with an offset loop thereof extending transversely through said apertures below said enfolded convolution portion to lock said enfolded convolution portion in said clip and being crimped upwardly around a portion of a convolution of an adjacent unit in the same row to interlock at each of said junctures said two convolutions, said tie wire and said clip.

8. In a spring assembly having a plurality of rows of coil spring units and tie wires for retaining units in one row in spaced relation to units in another row, said tie wires having spaced offset loops, in combination, interlocking means fastening adjacent portions of convolutions of units in one row with a tie wire comprising an apertured

clip folded over arcs of convolutions of two adjacent units and a tie wire offset loop extending through apertures in the legs of the fold of said clip below said convolutions to lock said convolutions in the folded clip, said offset loop terminating in crimped position to retain said tie wire interlocking relation with said clip and said convolutions.
